UNITED STATES PATENT OFFICE.

CHARLES F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

END-LASTING MECHANISM.

1,393,396.

Specification of Letters Patent. Patented Oct. 11, 1921.

Application filed January 13, 1919. Serial No. 270,864.

To all whom it may concern:

Be it known that I, CHARLES F. PYM, a subject of the King of England, residing at Lynn, in the county of Essex and State of Massachusetts, have invented certain Improvements in End-Lasting Mechanisms, of which the following description, in connection with the accompanying drawings, is a specification, like reference characters on the drawings indicating like parts in the several figures.

This invention relates to machines for working uppers over lasts, and more particularly to end-lasting mechanism for use in such machines. The invention is herein shown as embodied in toe lasting mechanism particularly designed for use in bed lasting machines, but it will be understood that in its broader aspects the invention is not limited to toe lasting means nor restricted in utility to machines of the particular type illustrated or to machines in which the operations are effected manually.

An object of the invention is to provide an improved construction of end lasting mechanism designed to facilitate accurate conformity of the wipers to the contour of the shoe and to insure precision in the closing movement of the wipers to cause them to wipe the margin of the upper inward over the shoe bottom a substantially uniform distance around the end and along the opposite sides of the shoe. With this and other objects in view, the invention provides, as an important feature, novel means constructed and arranged to permit a preliminary adjustment of the wipers to the contour of the shoe prior to their wiping movement inward over the shoe bottom.

The construction shown as an illustrative embodiment of the invention comprises manual means for effecting a preliminary movement of each wiper independently of the other to position its inner edge substantially contiguous to the lateral periphery of the shoe, and means automatically acting to lock the wipers against retractive movement independently of their operating means to cause them in their subsequent closing movement over the shoe bottom to be moved inward equal distances at the opposite sides, the machine being further constructed to cause the wipers to be released by the locking means in the return of the

parts to starting position. In the use of the construction shown, moreover, the wipers are first moved forward by their operating means substantially to the end face of the shoe and are then relatively adjusted laterally of the shoe, thus insuring a uniform inward movement over all portions of the margin of the shoe bottom around the end and along the opposite sides. In machines designed to effect an upwipe around the end of the toe prior to the overwiping action, as in the illustrative construction, such preliminary adjustment of the wipers to the contour of the shoe insures effectiveness in the upwiping operation around the entire end portion of the shoe, in addition to the manifest advantage in the overwiping operation, irrespective of any upwipe, of forcing the upper closely into the angle between the feather and the shoulder or rib of the sole or insole at all points without danger of damaging any portion of the shoulder or rib by reason of an unsymmetrical relation of the wipers to the shoe. It will be evident that with such a construction of end lasting mechanism the same wipers may be used effectively in lasting a comparatively wide range of sizes and styles of shoes.

The above and other features of the invention, including certain details of construction and combination of parts, will now be described with reference to the accompanying drawings and pointed out in the claims.

In the drawings,

Figure 1 is a plan view of end lasting mechanism in which the invention is embodied, portions of the mechanism being broken away to illustrate the interior construction, and

Fig. 2 is a view in front elevation on a smaller scale illustrating the application of the mechanism shown in Fig. 1 to the toe lasting portion of a bed lasting machine.

For purposes of illustration the invention is herein shown as embodied in mechanism particularly designed for use in a bed lasting machine of the general type disclosed in United States Letters Patent No. 1,018,477, granted on Feb. 27, 1912 upon an application of Matthias Brock, certain features of the construction illustrated in Fig. 2 being more fully described in United States Letters Patent No. 1,284,870 granted upon ap-

plication of Matthias Brock on Nov. 12, 1918. The toe lasting portion of machines of the illustrative type comprises a frame 2 having a guideway for a vertically movable stem 4 upon which the toe lasting mechanism is supported, the stem 4 being connected to a treadle (not shown) whereby the mechanism may be elevated to wipe the upper over the lateral periphery of the last 10 around the toe toward the edge of the shoe bottom. The stem 4 supports a bed plate 6 upon which is slidably mounted a supporting plate 8 adjustable lengthwise of the machine by means of a screw 10 operated by a hand wheel 12 to position the lasting mechanism properly in accordance with the length of the shoe, the shoe on its last being mounted as usual upon a heel spindle (not shown) with its toe end supported upon a 15 toe rest 14 mounted for adjusting movement lengthwise of the machine with the toe lasting mechanism. Mounted on the plate 8 is a support 16 adjustably movable laterally of the machine and carrying a plate 18 which is pivoted at 20 to swing laterally as determined by adjustment of a hand wheel 22. Upon the plate 18 are projections 24 arranged to support on a transverse pivot 26 a head 28 which is adjusted about the 25 pivot and maintained in adjusted position by means of a screw 30. The head 28 has a sleeve portion 32 providing a bearing for a hub 34 (Fig. 1) of the toe wiper head 36, this head being adjustable in its bearing by 30 means of a screw 38 to tip the toe wipers laterally in such manner as to adapt them to the lateral inclination of the forepart of the last bottom. Since the various features of the construction as thus far described may 35 be substantially as in prior machines of the illustrative type and as fully described in the prior patents above referred to, the application of the present invention to the prior type of machine will be readily understood without any further detailed description 40 of these well known parts.

The wiper head 36 in its front end portion is recessed to provide a slideway for a wiper support or carrier 40 which is secured to the 45 front end of an operating plunger 42 for bodily movement lengthwise of the shoe, the plunger 42 being connected at its outer end to a hand lever 44 whereby the operative movements of the wiper carrier are effected. 50 Mounted in a recess in the wiper carrier 40 are a pair of gear segments 46 which are grooved in their front edges to receive wiper plates 48. The wiper plates are locked to the supporting gear segments by pin and 55 slot connections 50 so constructed as to permit a limited bodily positioning movement of the wiper plates around the end of the shoe in response to their engagement with the shoe. The wiper plates 48 are pivoted 60 together at 52 for relative swinging move-

ments, the axis of the pivot 52 being substantially coincident with the axes of swinging movement of the gear segments 46 determined by rolls 54 which are mounted on studs secured to a cover plate 56 on the wiper 70 carrier 40 and engage in curved slots 58 in the gear segments.

For imparting operative closing movement to the gear segments 46 and their supported wiper plates, the wiper carrier 40 has 75 mounted thereon pinions 60 the teeth of which are in engagement with the teeth on the outer edges of the gear segments, these pinions being fast with smaller pinions 62, the teeth of which are in engagement with 80 teeth on rack bars 64 mounted in the wiper head 36. Collars 66 secured on the ends of the rack bar 64 are arranged to engage the wiper head 36 to limit lengthwise movement of the rack bars in one direction, the bars 85 being normally held with the collars 66 in engagement with the head, as shown in Fig. 1, by means of springs 68 connected at their opposite ends respectively to the rack bars and to portions of the wiper carrier 40 in 90 which the front ends of the rack bars are guided. It will be evident that with the rack bars 64 thus held stationary by the collars 66, as shown in Fig. 1, a forward movement of the wiper support 40 effected by 95 swinging the lever 44 will cause the pinions 60, 62 to be turned by their connection to the relatively stationary rack bars in directions to swing the gear segments 46 and their supported wipers inwardly toward the shoe during the bodily forward movement of the support 40 and the wipers.

For the purposes of this invention each of the rack bars 64 has fast thereon a block 70 having a pin and slot connection 72 with 100 a hand lever 74 which is pivoted at 76 on the wiper head 36. By moving one or the other of these hand levers in the direction of the arrow on Fig. 1 a preliminary lengthwise movement may be imparted to the connected rack bar 64 independently of the operating lever 44 and plunger 42 in a direction to turn the connected pinions 60, 62 and to swing the corresponding gear segment 46 and its supported wiper plate inwardly toward the shoe about the pivotal axis 52. In this way the operator is enabled to move one or both of the wiper plates, each independently of the other, for closing the wipers preliminarily into substantial conformity to the contour of the shoe at its opposite sides. In order to lock the wipers in such position of adjustment, each of the blocks 70 is provided with ratchet teeth 78 arranged to be engaged by a pawl 80 pivoted on the 115 wiper head 36. Each of the pawls 80 has connected therewith a lever arm 82 which is pivotally connected in turn to a bar 84 slidingly mounted for lengthwise movement in a block 86 which is swiveled in the cover 120

plate 56. A nut 88 on the bar 84 normally serves by engagement with block 86 to position the pawl 80 out of engagement with the ratchet teeth 78, as shown in Fig. 1. This is the normal position of the parts before any operative forward movement is imparted to the wiper carrier 40. On the opposite side of the block 86 from the nut 88 a spring 90 mounted on the rod 84 between the block 10 and head 92 on the rod serves as yielding means whereby, upon a forward movement of the wiper support 40, lengthwise movement is imparted to the rod 84 in a direction to swing the pawl 80 into engagement 15 with the teeth 78 in such manner as to cause the pawl to retain the rack bar 64 in any position to which it is moved by the operation of the lever 74.

In the operation of the machine to last 20 the toe portion of a shoe, after the usual adjustments have been made to position the toe lasting mechanism properly in accordance with the length of the shoe and to position the wipers in the correct angular relation 25 to the plane of the shoe bottom, the operator swings the lever 44 to move the wiper support 40 toward the shoe a sufficient distance to carry the intermediate portion of the wiping edges of the plates 48 substantially 30 up to the end face of the shoe. If the shoe is a welt shoe, for example, the wipers will thus be moved forward substantially into engagement with the end face of the shoe below the plane of the shoe bottom 35 preparatory to the upwiping operation. In this preliminary bodily movement of the wipers they are also closed inward to some extent toward the opposite sides of the shoe by the swinging movement of the gear segments 46 effected by the turning of the pinions 60, 62 through their connection with the relatively stationary rack bars 64, and the pawls 80 also are swung outward into 40 position to engage the teeth 78 on the blocks 70, as hereinbefore explained. The operator now observes the relation of the wipers to the shoe, and if more accurate conformity of the edges of the wipers to the contour of the shoe may be secured by swinging one or 45 both of the wiper plates farther inwardly toward the shoe prior to the closing movement of the wipers inwardly over the shoe bottom, he moves one or the other or both of the levers 74 to effect the required adjustment. It will be evident that the pawls 80, 50 previously rendered operative in the initial movement of the wiper support, will serve to retain the wipers in adjusted relation. Having positioned the wipers in this manner, the operator will, if the shoe is a 55 welt shoe, move the toe lasting head upwardly to effect the upwiping operation around the toe. If more than one upwiping movement is required, the operator may, 60 without affecting the position of the pawls

80 and the relative adjustment of the wipers, back off the wiper support 40 slightly and thus effect a partial opening movement of the wipers preparatory to the lowering of the toe lasting head and by forward movement 70 of the lever 44 may then close the wipers again to their former position prior to the second upwipe. Having effected the upwiping operation in the manner required and elevated the wipers to the plane of the shoe 75 bottom, the operator moves the hand lever 44 forwardly to close the wipers inwardly over the shoe bottom and effect the overwiping operation. It will be evident that by reason of the preliminary adjustment of the 80 wipers to the contour of the shoe the wiper plates 48 begin to close inwardly over the shoe bottom simultaneously at the end and the opposite sides of the shoe and are consequently moved a uniform distance inwardly from the edge around the entire toe portion of the shoe. This insures that the margin of the upper shall be forced closely into the angle between the feather and the shoulder or rib of the sole or insole in the 90 case of a welt shoe or a turn shoe without danger of injury to the shoe materials by reason of any unequal inward movement of the wiper plates. 95

Having wiped the upper into lasted position in the manner above explained and secured it in the usual way, the operator withdraws the wipers from engagement with the shoe by reverse movement of the lever 44 to its starting position. In this backward movement of the wiper carrier 40 the wipers are swung to their open position through the action of the rack and pinion mechanism, and through engagement of the swivel blocks 86 with the nuts 88 on the rods 84 100 the pawls 80 are returned to their inoperative position out of engagement with the ratchet teeth 78. The rack bars 64 are thus released from the adjusting mechanism and are permitted to return to their normal position relatively to the wiper head through the action of the springs 68, such return movement of the rack bars serving also to position the gear segments 46 and the connected wipers centrally of the wiper support as 105 indicated in Fig. 1. 110

While the invention has been described with particular reference to the operation of the machine upon a welt shoe, it will be understood that the invention in its broader 120 aspects is not restricted to use in the manufacture of shoes of any particular type.

Having described the invention, what I claim as new and desire to secure by Letters Patent of the United States is:

1. In mechanism of the class described, the combination with end embracing wipers, of operating means and connections between said means and the wipers for closing them inward laterally of a shoe, said connections 130

being constructed and arranged to permit relative lateral closing movement of the wipers independently of said operating means to adjust them to the shoe, and additional means controlled by the operative movement of the wipers for retaining the wipers in adjusted relation.

2. In mechanism of the class described, the combination with end embracing wipers, 10 of operating means and connections between said means and the wipers for closing them inward laterally of a shoe and for moving them reversely to starting position, said connections being constructed and arranged to 15 permit relative lateral closing movement of the wipers independently of said operating means to adjust them to the shoe, means for locking each wiper as thus adjusted against retractive movement independently of the 20 operating means, and mechanism automatically operative upon reverse movement of the wipers to render said locking means inoperative.

3. In mechanism of the class described, 25 the combination with end embracing wipers, of operating means and connections between said means and the wipers for closing them inward laterally of a shoe, said connections being constructed and arranged to permit 30 relative lateral closing movement of the wipers independently of said operating means to adjust them to the shoe, means for locking the wipers in adjusted relation, and mechanism constructed and arranged to 35 cause the locking means to release the wipers in the return of the parts to starting position.

4. In mechanism of the class described, the combination with end embracing wipers, 40 of operating means constructed to move the wipers forwardly toward a shoe, connections between said means and the wipers to cause the wipers to be closed inward laterally of the shoe by said forward movement, means 45 for adjusting said connections independently of the operating means to position the wipers relatively to the shoe, and means automatically operative to lock the wipers in adjusted relation and to release them in 50 the return of the parts to starting position.

5. In mechanism of the class described, the combination with end embracing wipers and means for operating said wipers, of 55 means for effecting a preliminary movement of each of the wipers independently of the other to adjust the wipers substantially to the contour of the lateral periphery of the shoe, and locking means mounted on a part of the machine normally stationary during 60 the operative movement of the wipers for retaining the wipers in adjusted relation to cause them to be closed inward equal distances from the edge of the shoe bottom by the subsequent action of the operating 65 means.

6. In mechanism of the class described, the combination with end embracing wipers, a support for said wipers mounted for movement lengthwise of a shoe, and independent connections to the different wipers to cause them to be closed inward laterally of the shoe by said movement of the wiper support, of means for moving said wiper operating connections each independently of the other to adjust the wipers relatively to the 70 shoe, means for retaining the wipers and their operating connections in adjusted relation, and mechanism for causing said retaining means to release the wiper operating connections and permit the wipers to resume 75 their normal relation to each other in the subsequent return of the wiper support to starting position.

7. In mechanism of the class described, the combination with end embracing wipers, 80 a support for said wipers mounted for movement lengthwise of a shoe, and independent connections to the different wipers to cause them to be closed inward laterally of the shoe by said movement of the wiper support, 85 of means for moving said wiper operating connections each independently of the other to adjust the wipers relatively to the shoe, and locking means arranged to be rendered operative by movement of the wiper support 90 toward the shoe to retain said connections in 95 adjusted position.

8. In mechanism of the class described, the combination with end embracing wipers, and means for operating said wipers, of 100 manual means for effecting a preliminary movement of the wipers independently of said operating means to adjust them substantially to the contour of the lateral periphery of the shoe, and mechanism controlled by said wiper operating means for retaining the wipers in adjusted relation 105 and for subsequently releasing them in the return of the parts to starting position.

9. In mechanism of the class described, 110 the combination with end embracing wipers and means for operating said wipers, of manual means for effecting a preliminary movement of the wipers independently of said operating means to adjust them substantially to the contour of the lateral periphery of the shoe, and pawl and ratchet mechanism arranged to be controlled by said wiper operating means for retaining the wipers in adjusted relation and for subsequently releasing them in the return of 115 the parts to starting position.

10. In mechanism of the class described, the combination with end embracing wipers, a support for said wipers mounted for movement lengthwise of a shoe, and connections to cause said wipers to be closed inward laterally of the shoe by said movement of the support, of means for moving said wiper operating connections each independently of 120 125 130

the other to adjust the wipers relatively to the shoe, and locking means connected to said wiper support and arranged to be rendered operative by the movement of the support to retain the wiper operating connections in adjusted relation and subsequently to release said connections.

11. In mechanism of the class described, the combination with end embracing wipers, 10 a support for said wipers mounted for movement lengthwise of a shoe, manual means for imparting operative movement to said support, and unyielding connections whereby closing movement laterally of the shoe is 15 imparted to the wipers by the movement of the support, of manual means comprising parts normally stationary in the operative movement of the wipers for effecting movement of said connections independently of 20 the movement of the wiper support to adjust the wipers relatively to the shoe, and mechanism for retaining the wipers in adjusted relation to cause them to be closed inward equal distances from the opposite sides of 25 the shoe through the subsequent operative movement of the wiper support.

12. In mechanism of the class described, the combination with end embracing wipers and means for operating said wipers, of 30 mechanism comprising levers mounted on a part of the machine normally stationary in the operative movement of the wipers and connected respectively to the different wipers to adjust them each independently of 35 the other substantially to the contour of the lateral periphery of the shoe prior to their inward closing movement over the shoe bottom.

13. In mechanism of the class described, 40 the combination with end embracing wipers, and means for operating said wipers, of mechanism comprising members mounted on a part of the machine normally stationary in the operative movement of the wipers for 45 adjusting the wipers independently of their operative movement substantially to the contour of the lateral periphery of the shoe, and locking means constructed and arranged to retain the wipers in adjusted relation.

14. In mechanism of the class described, the combination with end embracing wipers, a support for said wipers mounted for movement lengthwise of a shoe, and connections to the respective wipers to cause them to be 55 closed inward laterally of the shoe by said movement of the wiper support, of hand levers arranged to operate said connections each independently of the other to adjust the wipers relatively to the shoe, and means controlled by movement of the wiper support for retaining the wipers in adjusted relation and for subsequently releasing them.

15. In mechanism of the class described, the combination with end embracing wipers, 60 of mechanism comprising pinions and rack

bars for imparting operative closing movement to the wipers, means for moving said rack bars to adjust the wipers relatively to the shoe, and locking means constructed and arranged to retain the rack bars in adjusted 70 position and subsequently to release them to permit the wipers to resume their normal relation to each other.

16. In mechanism of the class described, the combination with end embracing wipers, 75 of gear segments connected to said wipers to close them inward over a shoe, pinions engaging said gear segments, rack bars connected to said pinions to operate them, and hand levers connected to the respective rack 80 bars for adjusting the wipers each independently of the other.

17. In mechanism of the class described, the combination with end embracing wipers, 85 of gear segments connected to said wipers to close them inward over a shoe, pinions engaging said gear segments, rack bars connected to said pinions to operate them, manual means for moving said rack bars lengthwise to adjust the wipers relatively to the 90 shoe, and pawl and ratchet mechanism for retaining the rack bars in adjusted position.

18. In mechanism of the class described, the combination with end embracing wipers, 95 of a support for said wipers mounted for movement lengthwise of a shoe, pinions carried by said support and connected to the wipers to close them, normally stationary rack bars connected to said pinions to render them operative in the movement of 100 the wiper support toward the shoe, manual means for moving said rack bars lengthwise each independently of the other to adjust the wipers relatively to the shoe, and pawl and ratchet mechanism for retaining the rack 105 bars in adjusted position.

19. In mechanism of the class described, the combination with end embracing wipers, 110 of a support for said wipers mounted for movement lengthwise of a shoe, pinions carried by said support and connected to the wipers to close them, normally stationary rack bars connected to said pinions to render them operative in the movement of the wiper support toward the shoe, means for moving 115 said rack bars lengthwise each independently of the other to adjust the wipers relatively to the shoe, and mechanism controlled by movement of the wiper support for retaining the rack bars in adjusted position and for 120 subsequently releasing them.

20. In mechanism of the class described, the combination with end embracing wipers, 125 of a support for said wipers mounted for movement lengthwise of a shoe, pinions carried by said supports and connected to the wipers to close them, normally stationary rack bars connected to said pinions to render them operative in the movement of the wiper support toward the shoe, manual 130

- means for moving each of said rack bars lengthwise independently of the other to adjust the wipers relatively to the shoe, ratchet teeth carried by said rack bars, and pawls 5 arranged to be controlled by the movement of the wiper support for engaging said teeth to retain the rack bars in adjusted position and for subsequently disengaging the teeth to permit the wipers to resume their normal 10 relation to each other.
21. In mechanism of the class described, the combination with end embracing wipers, of a support for said wipers mounted for movement lengthwise of a shoe, mechanism 15 arranged to be operated by said movement of the support for closing the wipers inward laterally of the shoe, manual means for operating said support to move the wipers initially into engagement with the end face of 20 the shoe and for subsequently closing them inward over the shoe bottom, manual means arranged to be operated while the wipers are positioned substantially contiguous to the end face of the shoe to close them ad- 25 justably toward the lateral periphery of the shoe, and means arranged to be rendered operative by said initial movement of the wiper support for retaining the wipers in adjusted relation.
22. In mechanism of the class described, the combination with end embracing wipers, of operating means and connections to the wipers for moving them bodily lengthwise of a shoe and imparting to them also pro- 30 portional closing movement laterally of the shoe, said parts being constructed and ar- ranged to permit relative adjustment of the wipers laterally of the shoe independently of said lengthwise movement to position 35 their inner edges in substantially contiguous relation to the side faces of the shoe while said edges are similarly positioned relatively to the end face of the shoe, and additional means for locking the wipers against re- 40 tractive movement independently of their operating means to cause them to be moved inward uniformly over the end and the op- 45 posite sides of the shoe and for subsequently releasing them in the return of the parts to 50 starting position.
23. In mechanism of the class described, the combination with toe end embracing wipers, of operating means constructed to enable the operator to move the wipers for- 55 ward preliminarily to position them sub- stantially contiguous to the toe end face of a shoe, between the bottom and the top of the shoe, manual means for swinging the wipers inwardly while they are thus positioned and 60 held against forward movement to carry their inner edges into substantially contiguous relation to the sides of the shoe, and means automatically operative to lock the wipers against retractive swinging move- 65 ment to cause them to be moved inward a uniform distance from the edge of the shoe bottom at the end and the opposite sides of the shoe in the subsequent overwiping operation.
24. In mechanism of the class described, 70 the combination with toe end embracing wipers and a shoe support, of operating means constructed to move said wipers for- ward preliminarily to position them con- 75 tiguous to the toe end face of a shoe on said support below the plane of the shoe bottom, means for swinging the wipers while they are thus positioned to carry their inner edges into contiguous relation to the sides of the shoe, means constructed to lock the wipers 80 against retractive swinging movement from substantially any position to which they may be moved in thus adjusting them to a shoe, and means for moving the wipers to upwipe 85 the upper around the end of the shoe while they are thus positioned prior to their over- wiping movement.
25. In mechanism of the class described, the combination with shoe positioning means and toe embracing wipers relatively ar- 90 ranged to permit the wipers to be closed around the toe end of a shoe at a distance from the plane of the shoe bottom for wiping the upper over the lateral periphery of the last prior to wiping it inwardly over 95 the bottom of the last, of operating connec- tions for the wipers constructed to permit each wiper to be adjusted independently of the other to the contour of the lateral periphery of the shoe, and additional mecha- 100 nism for locking the different wipers against retractive movement from the positions to which they are thus adjusted.
26. In mechanism of the class described, the combination with shoe positioning 105 means, of toe end embracing wipers mounted for advancing and relative closing move- 110 ments into engagement with the lateral periphery of the shoe around the toe to permit the upper to be wiped over the lateral periphery of the last toward the plane of the shoe bottom before it is wiped inwardly over the shoe bottom, operating connec- 115 tions for said wipers constructed to permit the wipers to be adjusted each inde- pendently of the other to the lateral periphery of the shoe after they have been advanced and partially closed around the end of the shoe, and locking mechanism auto- 120 matically operative in such adjustment of the wipers to hold them against retractive movement from adjusted position.
27. In mechanism of the class described, the combination with shoe positioning means, of end embracing wipers, a wiper support mounted for movement lengthwise of the shoe, operating connections for said wipers comprising parts normally station- 125 ary during the movement of the wiper sup- port and acting in response to such move- 130

ment to close the wipers inward laterally of the shoe, said normally stationary parts being movable to adjust the wipers to the contour of the shoe, and pawl and ratchet mechanism for holding said parts in adjusted position.

28. In mechanism of the class described, the combination with shoe positioning means, of end embracing wipers, a wiper support mounted for movement lengthwise of the shoe, operating connections for said wipers comprising parts normally stationary during the movement of the wiper support and acting in response to such movement 10 to close the wipers inward laterally of the shoe, manual means connected to said normally stationary parts to adjust the wipers to the contour of the shoe, and mechanism for holding said parts in adjusted position.

15 29. In mechanism of the class described, the combination with shoe positioning means, of end embracing wipers mounted for simultaneous forward movement lengthwise of the shoe and closing movement 20 laterally of the shoe, mechanism for imparting said movements to the wipers constructed to permit adjustment of the wipers laterally of the shoe independently of their forward movement, and locking mechanism 25 mounted on a part of the machine normally stationary during the operative movement 30 of the wipers for holding the wipers in adjusted relation.

30. In a machine of the class described,

the combination with shoe positioning means, of a wiper supporting head, a wiper support mounted on said head for movement toward and from the shoe, wipers carried by said support, connections between said wipers and the wiper head for swinging the wipers inward laterally of the shoe in the forward movement of the wiper support, said connections comprising parts manually movable for adjusting the wipers laterally of the shoe, and mechanism mounted on said wiper head for holding the wipers in adjusted position.

31. In a machine of the class described, the combination with shoe positioning means, of a wiper supporting head, a wiper support mounted on said head for movement toward and from the shoe, wipers carried by said support, connections between said wipers and the wiper head for swinging the wipers inward laterally of the shoe in the forward movement of the wiper support, said connections comprising parts manually movable for adjusting the wipers laterally of the shoe, locking mechanism mounted on said wiper head for holding the wipers in adjusted position, and connections between said locking mechanism and the wiper support for rendering said locking mechanism alternately operative and inoperative.

In testimony whereof I have signed my name to this specification.

CHARLES F. PYM.
